(57) **CLAIM**

The ornamental design for a conduit connector as shown and
described.

DESCRIPTION

FIG. 1 is a front right side view of a conduit connector
embodying our new design;

FIG. 2 is a rear, left side perspective view thereof.

FIG. 3 is a top view thereof.

FIG. 4 is a bottom view thereof.

FIG. 5 is a front view thereof.

FIG. 6 is a rear view thereof.

FIG. 7 is a left side view thereof; and,

FIG. 8 is a right side view thereof.

The references to “left,” “right,” “front,” “rear,” “top,” and
“bottom” in the figure descriptions are not meant to require
certain in-use orientation; the connector assemblies and
connectors according to the claimed design may be used in
any orientation.

Broken lines are used to illustrate features of the conduit
connector which form no part of the claimed design.
